[57] CLAIM

The ornamental design for an automobile tire, as shown and described.

DESCRIPTION

FIG. 1 is a front view of an automobile tire showing our new design, it being understood that the tread pattern repeats uniformly throughout the circumference of the tire;

FIG. 2 is a rear view;

FIG. 3 is a right side view;

FIG. 4 is a left side view;

FIG. 5 is an enlarged view of the portion 5—5 as shown in FIG. 1 of the front of the automobile tire; and,

FIG. 6 is an enlarged cross-sectional view taken along the line 6—6 of FIG. 5.
